DOOR CLOSER

Harry Shackleton, Wolverhampton, and Alfred Davis Pochin, Hammerwich, near Walsall, England

Application June 5, 1942, Serial No. 445,936
In Great Britain May 5, 1941

7 Claims.

(Cl. 16—49)

This invention relates to door closing devices incorporating a spring adapted to be wound on opening the door or other part to which it is applied and check means for controlling the closing movement of the door.

The invention particularly relates to the type of door closer in which the check means comprise a frictional device.

In door closers of the type mentioned incorporating brake means, the force of the frictional check is substantially the same for both the opening and closing movements of the door, and difficulties arise from the fact that static friction being greater than kinetic friction there is a tendency for the device to stick when stopped during its stroke, making it necessary for the movement of the door to be started again.

An object of the invention is to provide a door closer having an improved frictional check means whereby the above mentioned disadvantages are avoided.

According to the invention the closing movement of a door closer is controlled by differential band brake means.

The invention consists in a door closer incorporating check means comprising a differential band brake so arranged that the braking effect is greater in the closing movement than in the opening movement of the door.

The invention also consists in a door closer incorporating check means comprising a differential band brake wherein means are provided for partly or wholly releasing the brake during the opening movement of the door.

The brake release means may also control the action of the brake at one or more points during the closing movement of the door.

The brake release means may comprise a rotary cam or other means associated with the spindle of the door closer and co-operating with a regulating arm connected to the brake levers. Means may be provided for superimposing a back pressure when the brake is at its maximum effort.

In the accompanying drawing:

Figure 1 is a sectional elevation of a door closer according to the invention.

Figure 2 is a plan with the main arm removed and the casing in section.

Figure 3 is a plan view of a modification.

Figure 4 is a plan view of a further modification.

In carrying the invention into effect according to one convenient mode by way of example a casing or box 1 is provided having a horizontal partition 2 forming upper and lower compartments 3 and 4. In the lower compartment 4 a main spring (or springs) 5 is provided one end of which is anchored to the casing 1, the other end being secured to a spring cap 6. The spring

cap 6 is adjustably coupled to the lower end of a main spindle 7 which is secured to a boss 8 rotatable in a bearing 9 formed on the partition. At the upper end of the main spindle a main arm 10 is provided which is adjustably secured to a reduced portion 11 of a brake drum 12 by means of dog teeth 13.

The drum 12 is integral with the boss 8 and at the lower end of the latter dog or ratchet teeth 14 are provided by which the spring cap 6 is adjustably secured to the drum, and the main spindle assembly. The main spindle 7, drum 12, spring cap 6 and main arm 10 are held in the operative position by a nut 15 threaded on the main spindle.

The brake drum is located in the upper compartment and is provided with a surface formed of any suitable braking material 16. Co-operating with the drum is a flexible brake band 17 which may comprise a steel band. The brake drum may be geared to the spindle so as to provide a greater rotary movement of the drum.

The brake band 17 conveniently comprises an endless band and is secured to an eccentrically mounted anchor piece 18 by screws 20 in such a manner as to constitute a differential band brake, the anchor by its eccentric mounting forming two arms or levers of different length which pivot about the axis of the anchor. The anchor 18 is pivotally mounted upon a spindle 19 secured in the casing 1.

The arrangement of the arms or levers of the differential brake is such that the brake is more effective during the closing movement of the door.

For the purpose of controlling the action of the brake, for example for releasing the brake during the opening movement and just prior to the final closing movement cam means are provided co-operating with a regulating arm secured to the anchor of the brake band. Conveniently the cam means comprises a rotary cam 21 formed upon the portion 11 of the drum 12 so that it partakes of the movements of the drum. The regulating arm 22 is provided with a roller 23 engaging the cam 21 and is held up to the cam by a light leaf spring 24 secured in the casing. This spring 24, or other suitable means, provides the necessary contact between the brake band 17 and the drum 12 except when the cam 21 comes into operation to release the brake. The arrangement of the cam 21 may be such that the braking may occur at any desired part of the opening or closing movements of the door, or in both, or may not occur at all, depending upon the requirements of the design. For example the cam 21 may be such that the brake is released at about 15° before the door closes so that the full pressure of the main spring may come into operation.

The main arm 10 at its free end is provided with a roller on a vertical axis which engages in a channel element let into the frame of the door. As an alternative a channel member may be provided with lugs for securing it upon the surface of the frame or other suitable means, such as are used in existing door closers, may be employed for connecting the main arm to the door.

It is to be noted that the differential brake means are so arranged that during the closing movement of the door the brake is automatically put on in accordance with the known operation of differential band brake, while in the opening movement the brake does not operate and while this is the preferred arrangement, the brake may be designed to operate with an initial load on the regulating arm as by a suitable spring other than the light leaf spring referred to above.

In operation, during the opening movement of the door or other member to which the closer is applied, the main arm 10 winds up the main spring or springs 5. At the same time the brake is off except for the light contact produced by the leaf spring 24. On releasing the door the motion is reversed and the brake is applied immediately unless the roller 23 of the regulating or brake arm 22 is lifted by the cam 21 in which case the brake comes on as soon as the roller runs down the cam. The application of the brake will be automatically assisted by the light pressure of the leaf spring 24. The brake may be constantly applied throughout the closing movement or regulated at any point or points by the action and contour of the cam. Thus, if the cam 21 is provided with a single rise the brake may be effective until shortly before the door closes when the brake is released to allow the full pressure of the main spring 5 to give a slight slam to operate the latch. On the other hand, if the cam has several rises, the brake will have a number of off and on movements.

Instead of the roller 23 on the regulating arm 22 an adjustable screw may be provided or the arm may bear directly on the cam.

The brake band 17 may also comprise a strip instead of a continuous band, the ends being suitably secured to the eccentrically mounted anchor 18.

Instead of mounting the friction material 16 on the drum it may be secured to the brake band as indicated in Figure 3.

Means other than the rotary cam 21 may be provided for controlling the brake adjusting arm 22, for example a pin projecting from the main spindle 7 may be provided.

Referring to Figure 4, instead of the leaf spring 24, operating to hold the brake band on the drum, a dual purpose spring 25 may be provided. This spring 25 is secured to the brake band anchor 18 and operates between two adjustable screw stops 26, 27. The stop 26 serves to keep band 17 in contact with the drum 12. The stop 27 is for the purpose of controlling the maximum amount of braking effort as hereinafter explained.

It is well known that in band brakes of the type employed herein the heavier the load to be braked, the harder the brake is pulled on and the anchor 18 is pulled further over for a heavy load than with a light one. Thus the superimposition of a back pressure on the anchor in opposition to the pulling on will lessen the braking effect. This

back pressure is obtained by the engagement of the spring 25 with stop 27 which is adjusted so that the pulling on of the brake is lessened at its maximum. This has the effect of speeding up the first part of the closing of the door.

The dual purpose spring may be used in conjunction with the cam 21.

It will be appreciated that owing to the differential action of the brake resulting in a strong action during closing of the door and a relatively weak action during opening of the door, it may in some circumstances be unnecessary to provide the cam brake release means.

According to a modification the drum may be fixed to the case and the brake band with the pivot and anchor be arranged to rotate.

We claim:

1. A door closer having check means including a differential band brake comprising a drum and a band encircling the drum and connected to differential levers, arranged so that the braking effect is greater in the closing movement than in the opening movement of the door, and resilient means operatively connected to the differential levers adapted normally to hold the brake band on the drum to provide a preloading of the brake.

2. A door closer as claimed in claim 1, wherein the resilient means are arranged so that the self induced resistance of the brake automatically reduces or temporarily removes the preloading.

3. A door closer as claimed in claim 1, wherein the resilient means comprises a spring operatively connected to the differential levers and operating against an adjustable stop whereby the self induced resistance of the brake automatically reduces or temporarily removes the preloading.

4. A door closer having check means including a differential band brake comprising a drum and a band encircling the drum and connected to differential levers arranged so that the braking effect is greater in the closing movement than in the opening movement of the door, and resilient means operatively connected to the differential levers adapted normally to hold the brake on the drum to provide a preloading of the brake and to superimpose a back pressure on the brake band for controlling the maximum brake pressure.

5. A door closer as claimed in claim 4, wherein the resilient means comprises a spring operatively connected to the differential levers and operating between adjustable stops.

6. A door closer having check means including a differential band brake comprising a drum and a band encircling the drum, the ends of the band secured to pivoted anchor means forming the differential levers of the brake, a leaf spring secured to said anchor, and having a free end located between adjustable stops, said free end normally contacting one stop to provide a preloading of the brake, and adapted to contact the other stop to limit the maximum self induced resistance of the brake.

7. A door closer as claimed in claim 6, comprising a casing, a main spring one end of which is secured to the casing, a spring cap to which the other end of the spring is secured, said casing enclosing the differential band brake, said cap being secured to the drum of said brake, said anchor being pivotally mounted on the casing.
